UNITED STATES PATENT OFFICE.

HENRY C. HASKELL, OF NEW YORK, N. Y.

DESIGN FOR A FINGER-RING.

SPECIFICATION forming part of Design No. 14,142, dated July 31, 1883.

Application filed May 4, 1883. Term of patent 7 years.

To all whom it may concern:

Be it known that I, HENRY C. HASKELL, of the city, county, and State of New York, have invented a new and Improved Design for Finger-Rings, of which the following is a full, clear, and exact description.

Reference is to be had to the accompanying drawings, forming part of this specification, in which similar letters of reference indicate corresponding parts in both figures.

Figure 1 is a perspective view of my newly designed finger-ring, and Fig. 2 is an elevation of the same, these two views being deemed necessary to fully illustrate my design.

15 The leading feature of my design consists in a grooved shank having at the ends, where attached to the head or setting, scroll ornaments.

20 A represents the head or setting, which may be circular, oval, rectangular, or of any desired outline, and may have a flat or rounded face, as desired.

B is the shank, which has a longitudinal groove, C, formed in it, giving it an appearance of being double.

25 On the ends of the shank B, where they are attached to the head or setting A, are scroll ornaments D, which, in connection with the grooved or double shank, give the ring a neat, ornamental, and attractive appearance.

30 Having thus described my invention, I claim as new and desire to secure by Letters Patent—

35 The design for a finger-ring herein shown and described, the same consisting of a grooved or double shank having on its ends, where attached to the head or setting, scroll ornaments.

HENRY C. HASKELL.
